CLOCK SYSTEM.

No. 909,503.

Specification of Letters Patent.

Patented Jan. 12, 1909.

Application filed October 26, 1908. Serial No. 459,654.

To all whom it may concern:

Be it known that I, ERNEST E. YAXLEY, citizen of the United States, residing at Chicago, in the county of Cook and State of Illinois, have invented a certain new and useful Improvement in Clock Systems, of which the following is a full, clear, concise, and exact description, reference being had to the accompanying drawings, forming a part of this specification.

My invention relates to clock systems and resides in a clock system employing a master clock mechanism or master timing device that includes electro-magnetic mechanism for periodically winding the master clock or otherwise periodically storing energy in the motive device of the master clock mechanism, a relay, switching mechanism operable by the aforesaid electro-magnetic mechanism to energize the relay whenever said electro-magnetic mechanism is operated, and sub clocks or timing devices (one or more) in a circuit governed by the relay, the switch governed by the relay for the control of the sub clock circuit being adapted to be restored slowly to its normal condition after it is released by the magnet of the relay, thereby giving ample time for adjustment or operation of the timing devices in the sub clock circuit. The electro-magnetic devices of the sub clock, by maintaining the hands or other indicating elements of the sub clocks in synchronism with the master clock, constitute synchronizing devices, and I, therefore, do not wish to limit myself to sub clock mechanisms in which only electro-magnets are employed for operating the clocks. By means of my invention it is immaterial for how short a space of time the energizing circuit of the relay is closed, as the switch in the sub clock circuit is caused to resume its normal position with sufficient slowness to permit the electro-magnets of the sub clocks or timing devices to perform their functions.

Hitherto difficulty has been experienced in synchronizing because of the shortness of the time during which the synchronizing circuit for the said clocks was kept closed, it frequently happening that the circuits would not be kept closed long enough to permit the synchronizing function or the clock operating function to be performed.

In accordance with my invention, the advantages which I seek may be secured with-

out causing the mechanism that is actuated by the power device in which energy is stored by the electro-magnet, to operate a special switching mechanism, inasmuch as I am enabled to secure the results sought by mere circuit connections with the switching mechanism that is already employed in the master clock mechanism for including the electro-magnet of the master clock in circuit to replenish power in the power device and to open the circuit of said electro-magnet when power has been replenished, though I do not wish to be limited to the employment of this identical switching mechanism.

My invention may be employed in connection with the clock mechanism shown in my application Serial No. 424,760, filed April 2, 1908, wherein I have illustrated and claimed a clock mechanism including an electro-magnet, a power device in which energy is stored by the electro-magnet when energized, mechanism operable by said power device to enable the transmission of power therefrom to perform work, switching mechanism operated when the power device has transmitted energy replenished therein by the electro-magnet to close circuit through the electro-magnet, whereby energy in the power device may be replenished and operated when said electro-magnet has discharged its function of storing energy in the power device, to exclude the electro-magnet from circuit. I do not wish to be limited, however, in all embodiments of the invention to the employment of the master clock mechanism whose operating electro-magnet has circuit opened therethrough only when the armature of such electro-magnet has been fully attracted.

I will explain my invention more fully by reference to the accompanying drawing, showing an embodiment thereof as employed in connection with the clock mechanism forming the subject matter of my aforesaid copending application, the drawing illustrating the circuit relations of the parts diagrammatically.

The motor mechanism of the master clock that I have illustrated includes a clock train *a* in suitable relation with the hands of the clock, all as is well understood by those skilled in the art. The initial wheel *b* of the train *a* is in the form of a ratchet wheel, to which torque is initially applied for the purpose of operating the balance of the train.

in suitable gear relation with the wheel *b*. Torque is applied to the wheel *b* by means of an actuating pawl *c*, which is, in turn, operated by a spring *d*. The pawl *c* is pivoted 5 upon an armature *e* and power is effectively exerted upon the pawl *c* by the spring *d* through said armature, it being understood that this power is effectively exerted during the time that the magnet *f* provided for the 10 armature is in open circuit. When the armature has completed its normal receding movement from its electro-magnet, the circuit including the electro-magnet and a suitable source of current, as the battery *g*, is 15 closed between the contacts *h* and *i*, as will be presently described, whereby the tension of the spring *d* is increased for the purpose of renewing the power that is required to 20 operate the motor. During the attraction of the armature this circuit is maintained closed, as I will now describe. To accomplish this result in the embodiment of the invention shown, I enable the holding pawl or 25 detent *k* to act upon the spring contact *i* in such a manner that when the actuating pawl *c* has moved the wheel *b* its predetermined areal distance, preferably one tooth, the holding pawl will drop into engagement with a fresh tooth and permit the spring 30 contact *i* to engage the contact *h* by reason of the resiliency of the spring contact *i*, the spring contact *i* having been placed under increased tension by reason of the depression of the detent *k* during the movement 35 of the wheel *b* the space of one tooth. It will, therefore, be seen that the contact *i* practically travels with the detent *k*, so that when said detent engages a new tooth, it 40 closes circuit through the magnet.

In order to open the circuit, the spring *h* is lifted, which lifting operation takes place when the armature *e* has been fully attracted, it being understood that when the armature is fully attracted, the actuating pawl *c* 45 has engaged a fresh tooth, the pawl, when dropping into engagement with a fresh tooth, permitting an agency to effect the elevation of the contact *h*, which agency is desirably in the form of an adjustable spring *l* that is sufficiently strong to overcome the 50 tension of the spring *h*, said spring *l* preferably acting upon the spring *h* through the pawl *c* and a roller post *m*, constituting a cam element, carried upon said pawl, the 55 spring *h* having its end suitably upturned for engagement with said post, whereby the pawl mechanism has cam engagement with said spring *h*. The upturned end of the 60 spring *h* that engages the post *m* is so related to the surface of the tooth over which the nose of the pawl *c* rides, that during the time that the nose of said pawl is riding over said tooth surface the said tooth surface prevents the spring *l* from having 65 operative lifting action upon the upturned end

of the spring *h*, though during this movement the post *m* desirably does not leave the spring *h*. When the pawl has left the tooth surface over which it has ridden, the restraining influence of said tooth surface is removed, whereupon said pawl is brought into actuating engagement with the tooth over which it previously rode through the agency of the spring *l*, forming part of the pawl mechanism, which spring also lifts the contact *h* through the intermediation of said pawl and the post *m* carried thereby and engaging said spring *h*, so that the springs or contacts *h* and *i* are separated and are only separated when the pawl *c* has left the tooth surface over which it has ridden and has dropped into fresh tooth engagement. After the pawl has newly engaged a tooth, the circuit of the magnet *f* then being open, the power device *d* acts through the armature *e* to move the pawl *c* in a direction opposite to that in which it previously moved, whereby turning effort is applied to the initial wheel *b* by the power device *d* to operate the motor train. 90

The detent *k* operates to prevent the wheel *b* from turning in a direction opposite to that which it follows through the agency of the pawl *c* during the time that the pawl *c* is riding over a tooth, the detent *k* freshly 95 engaging a tooth when the pawl *c* has turned the wheel *b* a step. During the time that the pawl *c* is turning the wheel *b*, the detent *k* rides over a tooth surface preparatory to a fresh tooth engagement, during 100 which riding action of said detent the contact *i* is depressed, the contact spring *h* being inherently adapted to follow the spring *i* in its downward movement but being prevented from engaging the same, by reason 105 of the engagement of the contact *h* with the roller *m*. It is desirable to preserve an approximately fixed distance between the springs *h* and *i* when they are separated, to which end I preferably dispose the upturned 110 end of the spring *h* parallel with the surface of the tooth over which the detent *k* is riding. When the detent *k* has escaped the tooth surface over which it has ridden and drops into fresh tooth engagement, the 115 spring *i*, by reason of its own resiliency, makes contact with the spring *h*, it being understood that the detent *k* is mounted upon the spring *i* and is free of direct mechanical engagement with the spring *h*. 120

When the circuit of the electro-magnet is opened, the contact terminal *i* is stationary. The contact *i* is preferably made movable, as has been described, in order to simplify the construction, for in the embodiment shown 125 the contacts *h* and *i* may be moved relatively very quickly both in opening the circuit and in closing the circuit, a single pair of contacts being only required.

The relay circuit *n* is desirably opened and 130

closed by the same switching mechanism *h i* that is governed in the manner which has been described, the switch parts *h i* constituting terminals for the relay circuit *n* as well as terminals for the circuit of the magnet *f*, the battery *g* thus being common to the circuit of the magnet *f* and the relay circuit *n*. The relay circuit *n* includes a relay *o* having an armature *p* which is adapted to be attracted quickly, but which is retarded when being retracted by the retractile spring *q* by means of such suitable retarding device as that indicated at *r*, the mechanism *r* including a retarding fan *s* that is operated by the armature when being retracted. The armature carries a leaf spring *t* which is quickly moved and preferably then brought into engagement with a contact *u* when the armature *p* is attracted, the said armature being adapted to continue in its motion after the initial engagement of the spring *t* with the contact *u* so as to enable said elements *t* and *u* to remain in engagement for an appreciable length of time after the armature *p* has been released by the magnet of the relay *o*. In other words, the spring *t*, by being engaged with the contact *u* during the first part of the movement of the armature *p*, becomes a follow-up spring or contact serving to maintain engagement with the contact *u* after the armature *p* has moved an appreciable distance upon being retracted. The contacts *t* and *u* are in serial relation with a battery *v* included in the timing device circuit *w*, which circuit is shown with two parallel limbs between which timing devices *x* are connected, the circuit relation of one of the timing devices being shown somewhat more fully than the circuit relation of the remaining timing devices. There has been illustrated in connection with one of the timing devices an electro-magnet *y* in bridge between the limbs of the circuit *w* and in co-operative relation with the hand-operating mechanism *z* of the associate timing device.

As I have above pointed out, the contacts *h* and *i* are moved relatively very quickly, both in opening the circuit and in closing the circuit of the magnet *f*, and, consequently, of the relay *o*. The closure of the contacts *h* and *i* is in fact too short to enable the sub clocks or timing devices *x* to be directly connected with said elements *h* and *i*, on which account I interpose the relay mechanism *o* and the switching mechanism *t* and *u* between the master clock and the sub clocks *x*, as I have set forth.

While I prefer to employ as a switching device for controlling the circuit of the relay *o*, the same switching mechanism, *h i*, that is associated with the magnet *f*, I do not wish to be limited to the employment of the same switching mechanism in all embodiments of my invention.

I am aware that it is old to govern the

circuits of clocks to be synchronized by means of switching devices that are operated by the clock trains of clocks, which arrangements are radically different from the arrangement I have herein set forth, as will be well understood without particular explanation.

By means of my invention, no extra load is imposed upon the clock train that is actuated by the power device, whereby many advantages are gained. Moreover, by means of my invention the control of the circuit *w* may readily be adjusted within reasonable limits.

While I have herein shown and particularly described the preferred embodiment of my invention, I do not wish to be limited to the precise arrangement illustrated, as changes may be made without departing from the spirit of the invention.

Having thus described my invention, I claim as new and desire to secure by Letters Patent the following:

1. A master timing device including an electro-magnet, a power device in which energy is stored by the electro-magnet when energized, mechanism operable by said power device to enable the transmission of power therefrom to perform work, switching mechanism operated when the power device has transmitted energy replenished therein by the electro-magnet to close circuit through the electro-magnet, whereby energy in the power device may be replenished, and operated when said electro-magnet has discharged its function of storing energy in the power device, to exclude the electro-magnet from circuit, in combination with a relay whose circuit is governed by said switching mechanism, switching mechanism operated by the relay magnet and slow to be restored to normal when released by the relay magnet, and a circuit governed by the latter switching mechanism and including an electro-magnetically controlled timing device.

2. A master timing device including an electro-magnet, a power device in which energy is stored by the electro-magnet when energized, pawl mechanism operable by said power device to enable the transmission of power therefrom to perform work, a toothed wheel acted upon by said pawl mechanism, said pawl mechanism being operable by the electro-magnet for the purpose of enabling the pawl to engage a fresh tooth, switching mechanism operated when the power device has transmitted energy replenished therein by the electro-magnet to close circuit through the electro-magnet, whereby energy in the power device may be replenished, and operated by the pawl mechanism when the pawl of the pawl mechanism drops to engage a fresh tooth, to exclude the electro-magnet from circuit, said power device being coupled with the actuating pawl of the pawl mechanism to enable said pawl to transmit power from the power device to the toothed wheel.

in engagement with the pawl, in combination with a relay whose circuit is governed by said switching mechanism, switching mechanism operated by the relay magnet and slow to be restored to normal when released by the relay magnet, and a circuit governed by the latter switching mechanism and including an electro-magnetically controlled timing device.

- 10 3. A master timing device including an electro-magnet, a power device in which energy is stored by the electro-magnet when energized, pawl mechanism operable by said power device to enable the transmission of
15 power therefrom to perform work, a toothed wheel acted upon by said pawl mechanism, said pawl mechanism being operable by the electro-magnet for the purpose of enabling the pawl to engage a fresh tooth, a switching
20 device for closing circuit through the electro-magnet, whereby energy in the power device may be replenished, said switching device including a detent adapted for tooth engagement with said wheel, and acting, when
25 brought into fresh tooth engagement, to occasion the closure of said circuit, a switching device for excluding the electro-magnet from circuit and operated by the pawl mechanism when the pawl of the pawl mechanism
30 drops to engage a fresh tooth, said power device being coupled with the actuating pawl of the pawl mechanism to enable said pawl to transmit power from the power device to the toothed wheel in engagement with the
35 pawl, in combination with a relay whose circuit is governed by said switching mechanism, switching mechanism operated by the relay magnet and slow to be restored to normal when released by the relay magnet, and
40 a circuit governed by the latter switching mechanism and including an electro-magnetically controlled timing device.

4. A master timing device including an electro-magnet, a power device in which energy is stored by the electro-magnet when energized, pawl mechanism operable by said power device to enable the transmission of power therefrom to perform work, a toothed wheel acted upon by said pawl mechanism, 45 said pawl mechanism being operable by the electro-magnet for the purpose of enabling the pawl to engage a fresh tooth, a switching device for closing circuit through the electro-magnet, whereby energy in the power device may be replenished, said switching device including a detent adapted for tooth engagement with said wheel, and acting, when brought into fresh tooth engagement, to occasion the closure of said circuit, a 50 switching device for excluding the electro-magnet from circuit and operated by the pawl mechanism when the pawl of the pawl mechanism drops to engage a fresh tooth, said switching devices having a common 55 contact member which is actuated by the 60 65 70 75 80 85

pawl mechanism to exclude the electro-magnet from circuit and which is engaged by the contact governed by the detent to close circuit through the electro-magnet, said power device being coupled with the actuating pawl of the pawl mechanism to enable said pawl to transmit power from the power device to the toothed wheel in engagement with the pawl, in combination with a relay whose circuit is governed by said switching mechanism, switching mechanism operated by the relay magnet and slow to be restored to normal when released by the relay magnet, and a circuit governed by the latter switching mechanism and including an electro-magnetically controlled timing device. 70 75 80

5. A master timing device including an electro-magnet, a power device in which energy is stored by the electro-magnet when energized, mechanism operable by said power device to enable the transmission of power therefrom to perform work, switching mechanism operated when the power device has transmitted energy replenished therein by the electro-magnet to close circuit through the electro-magnet, whereby energy in the power device may be replenished, and operated when said electro-magnet has discharged its function of storing energy in the power device, to exclude the electro-magnet from circuit, in combination with a relay whose circuit is governed by said electro-magnet independently of the power device, switching mechanism operated by the relay magnet and slow to be restored to normal when released by the relay magnet, and a circuit governed by the latter switching mechanism and including an electro-magnetically controlled timing device. 85 90 95 100

6. A master timing device including an electro-magnet, a power device in which energy is stored by the electro-magnet when energized, pawl mechanism operable by said power device to enable the transmission of power therefrom to perform work, a toothed wheel acted upon by said pawl mechanism, said pawl mechanism being operable by the electro-magnet for the purpose of enabling the pawl to engage a fresh tooth, switching mechanism operated when the power device has transmitted energy replenished therein by the electro-magnet to close circuit through the electro magnet, whereby energy in the power device may be replenished, and operated by the pawl mechanism when the pawl of the pawl mechanism drops to engage a fresh tooth, to exclude the electro-magnet from circuit, said power device being coupled with the actuating pawl of the pawl mechanism to enable said pawl to transmit power from the power device to the toothed wheel in engagement with the pawl, in combination with a relay whose circuit is governed by said electro-magnet independently of the power device, switching mechanism 105 110 115 120 125 130

mechanism operated by the relay magnet and slow to be restored to normal when released by the relay magnet, and a circuit governed by the latter switching mechanism and including an electro-magnetically controlled timing device.

7. A master timing device including an electro-magnet, a power device in which energy is stored by the electro-magnet when energized, pawl mechanism operable by said power device to enable the transmission of power therefrom to perform work, a toothed wheel acted upon by said pawl mechanism, said pawl mechanism being operable by the electro-magnet for the purpose of enabling the pawl to engage a fresh tooth, a switching device for closing circuit through the electro-magnet, whereby energy in the power device may be replenished, said switching device including a detent adapted for tooth engagement with said wheel, and acting, when brought into fresh tooth engagement, to occasion the closure of said circuit, a switching device for excluding the electro-magnet from circuit and operated by the pawl mechanism when the pawl of the pawl mechanism drops to engage a fresh tooth, said power device being coupled with the actuating pawl of the pawl mechanism to enable said pawl to transmit power from the power device to the toothed wheel in engagement with the pawl, in combination with a relay whose circuit is governed by said electro-magnet independently of the power device, switching mechanism operated by the relay magnet and slow to be restored to normal when released by the relay magnet, and a circuit governed by the latter switching mechanism and including an electro-magnetically controlled timing device.

8. A master timing device including an electro-magnet, a power device in which energy is stored by the electro-magnet when energized, pawl mechanism operable by said power device to enable the transmission of power therefrom to perform work, a toothed wheel acted upon by said pawl mechanism, said pawl mechanism being operable by the electro-magnet for the purpose of enabling the pawl to engage a fresh tooth, a switching device for closing circuit through the electro-magnet, whereby energy in the power device may be replenished, said switching device including a detent adapted for tooth engagement with said wheel, and acting, when brought into fresh tooth engagement, to occasion the closure of said circuit, a switching device for excluding the electro-magnet from circuit and operated by the pawl mechanism when the pawl of the pawl mechanism drops to engage a fresh tooth, said switching devices having a common contact member which is actuated by the pawl mechanism to exclude the electro-

magnet from circuit and which is engaged by the contact governed by the detent to close circuit through the electro-magnet, said power device being coupled with the actuating pawl of the pawl mechanism to enable said pawl to transmit power from the power device to the toothed wheel in engagement with the pawl, in combination with a relay whose circuit is governed by said electro-magnet independently of the power device, switching mechanism operated by the relay magnet and slow to be restored to normal when released by the relay magnet, and a circuit governed by the latter switching mechanism and including an electro-magnetically controlled timing device.

9. A master timing device including an electro-magnet, a power device in which energy is stored by the electro-magnet when energized, mechanism operable by said power device to enable the transmission of power therefrom to perform work, switching mechanism operated when the power device has transmitted energy replenished therein by the electro-magnet to close circuit through the electro-magnet, whereby energy in the power device may be replenished, and operated when said electro-magnet has discharged its function of storing energy in the power device, to exclude the electro-magnet from circuit, in combination with a relay whose circuit is governed by said electro-magnet independently of the mechanism for the operation of which the power device is employed, switching mechanism operated by the relay and slow to be restored to normal when released by the relay magnet, and a circuit governed by the latter switching mechanism and including an electro-magnetically controlled timing device.

10. A master timing device including an electro-magnet, a power device in which energy is stored by the electro-magnet when energized, pawl mechanism operable by said power device to enable the transmission of power therefrom to perform work, a toothed wheel acted upon by said pawl mechanism, said pawl mechanism being operable by the electro-magnet for the purpose of enabling the pawl to engage a fresh tooth, switching mechanism operated when the power device has transmitted energy replenished therein by the electro-magnet to close circuit through the electro-magnet, whereby energy in the power device may be replenished, and operated by the pawl mechanism when the pawl of the pawl mechanism drops to engage a fresh tooth, to exclude the electro-magnet from circuit, said power device being coupled with the actuating pawl of the pawl mechanism to enable said pawl to transmit power from the power device to the toothed wheel in engagement with the pawl, in combination with a relay whose circuit is governed by said electro-magnet independ-

ently of the mechanism for the operation of which the power device is employed, switching mechanism operated by the relay and slow to be restored to normal when released 5 by the relay magnet, and a circuit governed by the latter switching mechanism and including an electro-magnetically controlled timing device.

11. A master timing device including an 10 electro-magnet, a power device in which energy is stored by the electro-magnet when energized, pawl mechanism operable by said power device to enable the transmission of power therefrom to perform work, a toothed 15 wheel acted upon by said pawl mechanism, said pawl mechanism being operable by the electro-magnet for the purpose of enabling the pawl to engage a fresh tooth, a switching device for closing circuit through the electro-magnet, whereby energy in the power 20 device may be replenished, said switching device including a detent adapted for tooth engagement with said wheel, and acting, when brought into fresh tooth engagement, 25 to occasion the closure of said circuit, a switching device for excluding the electro-magnet from circuit and operated by the pawl mechanism when the pawl of the pawl mechanism drops to engage a fresh tooth, 30 said power device being coupled with the actuating pawl of the pawl mechanism to enable said pawl to transmit power from the power device to the toothed wheel in engagement with the pawl, in combination with a 35 relay whose circuit is governed by said electro-magnet independently of the mechanism for the operation of which the power device is employed, switching mechanism operated by the relay and slow to be re- 40 stored to normal when released by the relay magnet, and a circuit governed by the latter switching mechanism and including an electro-magnetically controlled timing device.

12. A master timing device including an 45 electro-magnet, a power device in which energy is stored by the electro-magnet when energized, pawl mechanism operable by said power device to enable the transmission of power therefrom to perform work, a toothed 50 wheel acted upon by said pawl mechanism, said pawl mechanism being operable by the electro-magnet for the purpose of enabling the pawl to engage a fresh tooth, a switching device for closing circuit through the 55 electro-magnet, whereby energy in the power device may be replenished, said switching device including a detent adapted for tooth engagement with said wheel, and acting, when brought into fresh tooth engagement, 60 to occasion the closure of said circuit, a switching device for excluding the electro-magnet from circuit and operated by the pawl mechanism when the pawl of the pawl mechanism drops to engage a fresh tooth, 65 said switching devices having a common

contact member which is actuated by the pawl mechanism to exclude the electro-magnet from circuit and which is engaged by the contact governed by the detent to close circuit through the electro-magnet, said power device being coupled with the actuating pawl of the pawl mechanism to enable said pawl to transmit power from the power device to the toothed wheel in engagement with the pawl, in combination with a relay 70 whose circuit is governed by said electro-magnet independently of the mechanism for the operation of which the power device is employed, switching mechanism operated by the relay and slow to be restored to normal 75 when released by the relay magnet, and a circuit governed by the latter switching mechanism and including an electro-magnetically controlled timing device.

13. A master timing device including an 80 electro-magnet, a power device in which energy is stored by the electro-magnet when energized, mechanism operable by said power device to enable the transmission of power therefrom to perform work, switching mechanism operated to close circuit through the electro-magnet, whereby energy in the power device may be replenished, and operated after circuit has been closed 85 through said electro-magnet, to exclude the electro-magnet from circuit, in combination with a relay whose circuit is governed by said switching mechanism, switching mechanism operated by the relay magnet and slow to be restored to normal when released 90 by the relay magnet, and a circuit governed by the latter switching mechanism and including an electro-magnetically controlled 95 timing device.

14. A master timing device including an 100 electro-magnet, a power device in which energy is stored by the electro-magnet when energized, mechanism operable by said power device to enable the transmission of power therefrom to perform work, switching mechanism operated to close circuit through the electro-magnet, whereby energy in the power device may be replenished, and operated after circuit has been closed 105 through said electro-magnet, to exclude the electro-magnet from circuit, in combination with a relay whose circuit is governed by said electro-magnet independently of the power device, switching mechanism operated by the relay magnet and slow to be re- 110 stored to normal when released by the relay magnet, and a circuit governed by the latter switching mechanism and including an electro-magnetically controlled timing device.

15. A master timing device including an 115 electro-magnet, a power device in which energy is stored by the electro-magnet when energized, mechanism operable by said power device to enable the transmission of power therefrom to perform work, switch- 120

ing mechanism operated to close circuit through the electro-magnet, whereby energy in the power device may be replenished, and operated after circuit has been closed 5 through said electro-magnet, to exclude the electro-magnet from circuit, in combination with a relay whose circuit is governed by said electro-magnet independently of the mechanism for the operation of which the 10 power device is employed, switching mechanism operated by the relay and slow to be restored to normal when released by the

relay magnet, and a circuit governed by the latter switching mechanism and including an electro-magnetically controlled timing 15 device.

In witness whereof, I hereunto subscribe my name this 23rd day of October A. D., 1908.
